UNITED STATES PATENT OFFICE

2,511,169

WHEELED FIGURE TOY

Theodore E. McAvoy, Chicago, Ill.

Application August 9, 1947, Serial No. 767,799

2 Claims. (Cl. 46—100)

1

My invention relates to baby strollers having attached thereto a form of animated toy.

An important object of my invention is to provide a baby stroller of tricyclic construction, on the front wheel of which is mounted an animated toy; the animation being provided by a pendulating and frictional action. The wheels of the toy riding in a groove in the outer circumference of the front wheel, and the pendulating action being caused by a counterweight mounted on a disc set eccentrically on the hub of the said wheel. The said wheels of the toy being kept in constant contact with the rim of the stroller wheel by their mounting wire rods, which are attached to the eccentric disc, and are bent to provide the necessary resiliency to keep the wheels in contact with the rim of the front stroller wheel.

A further object of my invention is to provide an animated toy: in this instance, a cyclist mounted upon a bicycle, the wheels of which are caused to revolve by the front stroller wheel and give animation to the legs of the cyclist while the stroller is being propelled either forward or backward.

A still further object of my invention is to provide an animated toy that is caused to ride in a predetermined arcuate course upon the outer rim of the central front wheel of the tricycle in an up and forward, down and backward movement, while the stroller is being propelled either forward or backward.

Other objects and advantages inherent in my invention will become readily apparent from the ensuing description and the accompanying drawings, in which like parts are designated by like numerals, and in which:

Fig. 1 represents a perspective view of my invention showing an infant, in dotted lines, in the cab thereof.

Fig. 2 represents a side view of the animated toy connected to the front wheel of my invention.

Fig. 3 represents a side view of the front wheel of my invention showing its connected animated toy in two positions: one solid, and one in dotted position.

Fig. 4 represents a side view of the front wheel of my invention showing its connected animated toy in two reversed positions: one in solid lines; one in dotted lines, indicating the path of travel.

Fig. 5 is a cross-sectional view of my invention taken substantially on lines 5—5 of Fig. 4.

Fig. 6 is a cross-sectional view of a portion of my invention taken substantially on lines 6—6 of Fig. 3.

Referring to the illustrations, my invention is

2

generally designated 7 and consists of a frame 8, on which is mounted a cab 9. On the rear part of the frame 8 beneath the cab 9 are mounted two wheels 10, one on each side. On the back end of the cab 9 are mounted handle bars 11, used for propelling the stroller forward or backward. The front end of the frame 8 is forked at 12. The inside of the fork 12 being countersunk at 13 to provide a bearing for the axle 14 of the front wheel 16, which revolves upon the axle 14 by means of its bearing 15.

Also revolving upon the bearing 15 is a disc 17, which is mounted eccentrically thereon. On an arm 18 attached to the disc 17 is mounted a weight 19, held by bolt 20 in nut 33. Also mounted on the disc 17, opposite the arm 18, are two wire rods 21, bent at 22 to provide the proper resiliency to keep the wheels 24 and 25 of the bicycle 26 in constant and varied frictional contact with the groove 28 on the rim of the wheel 16. The outer end of the arms 21 are bent at 23 to provide hubs for the bicycle wheels 24 and 25.

The bicycle wheel 24, by means of a belt 35 and pedals 36, causes the legs of the cyclist 27 to pump up and down, as shown by dotted lines in Fig. 2, when the bicycle wheels 24 and 25 are frictionally revolved by the turning of the wheel 16 as the stroller 7 is propelled forwardly or backwardly by pushing or pulling on the handle bars 11. A strap 32 may be attached to the cab 9 to keep an infant or child 34 safely seated in the cab.

When the stroller 9 is standing still, the weight 19 will cause the bicycle toy 26 to be positioned at the top of the wheel 16. As the stroller is propelled forward by the handle bars 11, the revolving of the wheel 16 will, by means of its rim groove 28, cause the wheels 24 and 25 of the bicycle 26 to rotate, as has been previously described, animating the cyclist 27. As the stroller is propelled forward, friction between the wheel 16 and the bicycle wheels 24 and 25 is gradually increased, slowly propelling the bicycle 26 backwardly in the direction of the arrows 29 in Fig. 4, the weight 19 being revolved in the direction of the arrow 30.

As the bicycle 26 reaches the position shown by dotted lines in Fig. 4, the disc 17, to which it is eccentrically mounted, causes an easing of the frictional contact between the bicycle wheels 24 and 25 and the stroller wheel 16 so that the weight 19, which is oppositely positioned upon the disc 17, will begin swinging in the direction of the arrow 31 in Fig. 3, causing the bicycle 26 to move from the position, shown in solid lines in Fig. 3, to the position shown by dotted lines in

the same figure. This initiates a pendulating action of the arm 18 and the weight 19 causing the bicycle 26, together with the cyclist 21, to move upward and forward, and backward and downward in a restricted arc as shown in the Figs. 1, 3, and 4. This pendulating motion will continue so long as the stroller 9 is being propelled, either forwardly or backwardly.

An animated toy mounted and controlled in this manner will, by its advancing and retreating action, be sure to keep the attention of any infant or child riding in the cab of the stroller, providing a sure means of amusement and diversion for the said infant or child.

It will be understood that modifications of the structural features of my invention may be resorted to without departure from the nature or spirit of my invention, and I wish that my invention be construed as of the scope defined in the subjoined claims.

Having thus disclosed and revealed my invention, what I claim as new and desire to secure by Letters Patent is:

1. In a stroller toy of the character described having a forward traction wheel, toy support means mounted eccentrically on the axle of the said traction wheel, a bicyclist toy mounted resiliently on the said toy support means and having its wheels in frictional contactual relationship with the said traction wheel at its periphery, and pendulating means secured to the said toy support means in substantially diametral relationship to the said bicyclist toy.

2. In a stroller toy of the character described a forward traction wheel, toy support means mounted eccentrically on the axle of the said traction wheel, a bicyclist toy mounted resili-

ently on the said toy support means and having its wheels in frictional contactual relationship with the said traction wheel at its periphery, and pendulating means secured to the said toy support means in substantially diametral relationship to the said bicyclist toy, one of the wheels of the said bicyclist toy being connected to the pedal structure thereof by transmission means effectuating rotation of the said pedal structure, the feet of the said bicyclist being articulate and being secured to the said pedal structure to effectuate animation of the said bicyclist toy during forward and reverse movements of the said traction wheel.

THEODORE E. McAVOY.
